UNITED STATES PATENT OFFICE.

GEORGE A. WEHNER, OF SAVANNAH, GEORGIA.

PERMUTATION-LOCK.

1,103,116.

Specification of Letters Patent. Patented July 14, 1914.

Application filed March 17, 1913. Serial No. 754,848.

To all whom it may concern:

Be it known that I, GEORGE A. WEHNER, a citizen of the United States, and a resident of Savannah, in the county of Chat- 5 ham and State of Georgia, have invented a new and useful Improvement in Permutation-Locks, of which the following is a specification.

My invention is an improvement in per- 10 mutation locks, and has for its object the provision of a lock of the character specified, designed for use with automobiles, and ar- ranged to alternately connect a source of 15 electrical energy with the motor to start the same and with the magneto, wherein the lock is normally prevented from movement by releasable mechanism, operated by a se- 20 lection from a plurality of push pins of a series, wherein the selection of push pins may be varied to provide for changes in the combination, and wherein the changing 25 mechanism is normally locked in an inactive position and may be released only by oper- ating the proper selection of push pins.

25 In the drawings:—Figure 1 is a perspective view of the improved lock, Fig. 2 is an enlarged vertical section, Fig. 3 is a rear view of the operating mechanism, Fig. 4 is a transverse vertical section of the operat- 30 ing dial or knob, showing the parts in one position, Fig. 5 is a similar view showing the parts in another position, Fig. 6 is a perspective view of one of the push pins, Fig. 7 is a similar view of another of the 35 said pins, and Fig. 8 is a side view of the actuating sleeve of the lock.

The present embodiment of the invention is shown connected with a plate 1, which forms a closure for a receptacle or recess in 40 that portion of the hood 2 of an automobile which is directly in front of the driver, and the opening of the recess is inclosed by a frame 3, secured to the hood, the plate 1 closing the opening of the said frame and 45 concealing the recess from view.

The frame 3 is secured to the plate 2 of the hood by means of screws 4 or the like, and it will be noticed that the plate 1 is provided at its upper end with an inwardly 50 off-set longitudinally extending lug 5, which is received in a notch or recess 6, on the inner face of the plate 2 of the hood. The plate is held in place at its lower end by means of a bolt or latch 7, mounted to slide 55 in a bearing 8 on the rear face of the plate.

The plate is slotted as indicated at 9 at

the lower end thereof, and a screw 10 is passed through the slot and threaded into the bolt 7, for operating the said bolt, the head of the screw being on the outer face 60 of the plate. When the bolt or latch 7 is moved upwardly in the bearing 8 by means of the screw 10, the lower end of the bolt releases its engagement with the frame 3, and the plate and its attachments may be re- 65 moved from the opening in the plate 2 of the hood.

The bolt is provided with an inwardly offset upwardly extending lug 11, for a pur- 70 pose to be described, and for the additional purpose of limiting the downward move- 75 ment of the bolt. That portion of the bolt which engages the frame 3 is outwardly off- set to form a shoulder 12, between the said portion and the body of the bolt, and the said shoulder 12 engages a similar shoulder 13 on the plate to limit the upward move- 80 ment of the bolt.

The plate 1 is provided near its upper end and on its outer face with a circular recess 85 14, and with an opening 15 at the center of the said recess. The operating sleeve 16 is provided with a cylindrical hub or bushing 17, which extends through the opening 15 in the plate, and a collar or ring 19 encircles 85 the said hub or bushing on the inner side of the plate and holds the said sleeve from out- 90 ward movement, a set screw 21 passing through the ring or collar and engaging the hub or bushing to prevent displacement of the ring or collar.

A pin or rod 22 is arranged in the hub or bushing 17, the said rod having a head 23 at its outer end, and the inner end of the rod is conical as indicated at 24. The rod is 95 movable longitudinally of the hub, and a cross pin or key 25 is provided for limiting the outward movement of the rod.

A cylindrical knob 26 is arranged within 100 the operating sleeve 16, and the said knob is provided with a co-axial flange or sleeve 27 which fits outside of the said sleeve 16, the body of the knob fitting within the sleeve and filling the same. The knob is also pro- 105 vided with an annular radial flange 28, which extends beyond the sleeve 27, and the outer face of the said sleeve 27 is provided with a plurality of recesses 29, each of which has its side edges undercut as indicated at 30, and plates 31 are fitted in the recess, the 110 said plates having their side edges beveled to engage the undercut walls 30 of the recess.

It will be noted from an inspection of Figs. 2, 4 and 5, that the body of the knob 26 is provided with two series of radial openings 32, the members of each series being spaced at angular distances of 90° with respect to each other and the members of one series alternating with the members of the other series. A coil spring 33 is seated in each of the said openings, and a push pin 10 engages the outer end of each spring. The operating sleeve 16 is provided with two annular series of circumferentially extending slots 34, each slot having a circular enlargement 34^a at its center.

15 The push pins, before mentioned, are movable in the slots 34, and the sleeve 27 of the knob is provided with openings registering with the slots 34 and with the openings 32 of the body of the knob. The curved plates 20 31 are provided with slots 35, the said slots extending to the outer edges of the plates for receiving the pins before mentioned.

25 The push pins are divided into two series, one series being arranged nearer the plate than the other. The pins are shown in Figs. 6 and 7 and each series consists of four pins, two as shown in Fig. 6 and two as shown in Fig. 7. Each of the pins shown in Fig. 6 comprises a head 36, a cylindrical inner end 37, a portion 38 substantially rectangular in cross section adjacent to the head, a portion 39 substantially rectangular in cross section adjacent to the inner end and a connection 40 between the 30 two portions 38 and 39. Each of the pins shown in Fig. 7 comprises a head 36^a, a cylindrical inner end 37^a, a cylindrical central portion 40^a and portions 38^a and 39^a substantially rectangular in cross section adjacent to the head and the cylindrical portions 45 respectively. The sleeve 27 of the knob is provided with an inwardly extending pin 41, which is the operating pin for the mechanism to be operated. The said pin moves in an arc-shaped slot 42, in the plate 1, before mentioned. The sleeve 16 is prevented from rotation on the plate by means of screws 43, which are passed through from the rear face of the plate and engage the 50 said sleeve to hold the same rigid with respect to the plate. On this account it will be evident that to permit the rotation of the knob to operate the pin 41, the push pins must be in such position that a flattened or 55 substantially rectangular portion of each pin will engage the slot 34 through which the pin passes. All of the said pins are normally held in outward position by the springs and in the normal condition of the 60 knob, any or all of the said pins may be pressed inward without resistance. Certain of the pins however must be pressed inward to permit the rotation of the knob, and the other pins are so arranged that should any 65 except the selected pins be pressed inward,

the knob cannot rotate. In other words, the selected pins and only the selected pins must be pressed inward to permit the knob to properly operate.

70 The pins are numbered on the face of the knob or dial as indicated in Fig. 1, the numbers running from 1 to 8 clockwise. It will be noted from an inspection of Fig. 4 that two pins, namely 1 and 3, are out of register with the sleeve 16, that is, the said pins have their cylindrical portions 37 in the 75 portions 34^a of the respective slots 34 of the sleeve 16. When the said pins 1 and 3 are pushed inwardly until the heads 36 thereof contact with the plates 31, the flattened or substantially rectangular portion 39 of each pin will be moved into the portion 34^a of the slot 34, and the knob may move freely in either direction. The pins are divided into two series as before stated, 80 a negative or passive series, which normally stand in a position to offer no resistance to the rotation of the knob, and which when pressed inwardly will prevent the rotation of the knob, and a positive series which 85 must be pressed in before the knob can be rotated, and which in normal position will prevent the rotation of the knob. The first-named series are shown in Fig. 7 and the last-named in Fig. 6.

90 To change the combination of the knob or dial, the knob must be turned to the right or the left, after the proper selection of pins have been operated to move the pin 95 41 from its position directly above the lug 11 of the bolt. The said pin 41 normally stands directly above this lug, and prevents the movement of the bolt. After the knob has been turned to release the bolt, the bolt is pressed upwardly and the lower edge of 100 the plate 1 is disengaged from the opening of the hood. The lifting out of the lower end releases the upper end. The dial or 105 knob is then removed from the plate by removing the set screw 21 withdrawing the 110 screws 43 and after the knob has been removed, the plates 31 may be slipped outwardly away from the flange 28 to permit the removal and replacement of the push pins. In this manner any desired combination or selection may be provided for and the combination may be changed as often 115 as necessary.

120 It will be noticed from an inspection of Fig. 3 that a pair of levers 70 and 70^a is pivoted on the hub or bushing 17 of the operating sleeve. Each lever is provided at its upper end with a lateral lug 71 and a coil spring 72 is arranged between the lugs. The lower end of the lever remote from the plate 1 is offset inwardly toward the plate, as indicated at 73, to cause the lower ends of the levers to lie in approximately the same plane, and the said lower ends of the levers engage on opposite sides of the pin 41. 125 130

The plate 1 is provided with a stop 11^a, and the said lower ends of the levers 70 and 70^a engage opposite sides of the stop.

It will be evident that when the pin 41 is moved in either direction, that lever toward whose lower end the pin is moved, will be swung away from the other lever, thus placing the spring 72 under tension. As for instance, when the pin is swung 10 toward the lower end of the lever having the offset portion 73, the said lever will be swung as indicated in dotted lines in Fig. 3, and as soon as pressure on the lever is released, the spring 72 will tend to return the 15 lever to its original position, thus moving the pin 41 to normal position. The lever from which the pin moves is prevented from movement by the stop 11^a.

The operation of the lock is as follows: To 20 permit the knob to turn, the push pins of the active series are pressed inwardly against the resistance of the springs, until the heads thereof engage the outer surfaces of the plates 31. This movement of the pins moves 25 the cylindrical portion of the said pins inwardly so that the said cylindrical portions no longer register with the openings 34^a of the sleeve 16, but instead a flattened portion, and the knob is ready to turn, the flattened 30 portion of the push pins moving in the slots 34. The knob may be moved in either direction, and when restored to its original position and the pins are released, they are moved outward, thus again locking the knob 35 to the sleeve. Should for instance the combination be 1, 4 and 7, the pins 1, 4 and 7 are depressed. Should any of the pins of the passive series be depressed the knob will be held from angular movement, even though 40 the correct pins of the active series were in proper position, since the pins of the passive series normally stand with a flattened portion registering with the slots 34.

I claim:—

45 1. A lock of the character specified, comprising a plate having a central opening, a sleeve having a plurality of series of longitudinally extending alined slots, each slot having a substantially circular enlargement 50 intermediate its ends, said sleeve having a hub received in the opening of the plate, a pin passing through the hub, a knob comprising a body received within the sleeve and having an annular radially offset flange fitting outside the sleeve, the said body having 55 an opening for the pin, said body and flange having alined circular openings adapted to register with the enlargements of the slots, push pins in the openings, a spring normally 60 pressing each of the said push pins outward, each of the said pins having a head for limiting the inward movement thereof, and having transversely flattened portions for moving in the slots of the sleeve to permit the knob to move angularly with respect to 65 the sleeve when the said push pins are in predetermined positions with respect to the sleeve, the flange having an inwardly extending pin, and the plate having an arc-shaped slot through which the pin extends, 70 the said flange having on its outer face a plurality of undercut recesses, said recesses intersecting the openings, curved plates having beveled edges fitting the recesses and having slots extending transversely of the flange and registering with the openings thereof, each of the said push pins having a transversely flattened portion adjacent to the head and fitting a slot of a plate to limit the outward movement of the pin, mechanism adapted to be operated by the movement of the pin of the flange, and releasing mechanism adapted to be operated by the pin of the hub. 75

80 2. A lock of the character specified, comprising a plate having a central opening, a sleeve having a plurality of series of longitudinally extending alined slots, each slot having a substantially circular enlargement intermediate its ends, said sleeve having a hub received in the opening of the plate, a pin passing through the hub, a knob comprising a body received within the sleeve and having an annular radially offset flange fitting outside the sleeve, the said body having an opening for the pin, said body and flange having alined circular openings adapted to register with the enlargements of the slots, push pins in the openings, a spring normally pressing each of the said push pins outward, each of the said pins having a head for limiting the inward movement thereof and having transversely flattened portions for moving in the slots of the sleeve to permit the knob to move angularly with respect to the sleeve when the said push pins are in predetermined positions with respect to the sleeve, the flange having an inwardly extending pin and the plate having an arc-shaped slot through which the pin extends, and mechanism adapted to be operated by the movement of the pin of the flange, and means on the said mechanism for engagement by the pin of the hub to return the said mechanism to its original position. 90

95 3. A lock of the character specified, comprising a plate having a central opening, a sleeve having a plurality of series of longitudinally extending alined slots, each slot having a substantially circular enlargement intermediate its ends, said sleeve having a hub received in the opening of the plate, a knob comprising a body received within the sleeve and having an annular radially offset flange fitting outside the sleeve, the said body having an opening for the pin, said body and flange having alined circular openings adapted to register with the enlargements of the slots, push pins in the openings, a spring normally pressing each of the said push pins outward, each of the said pins having a head for limiting the inward movement thereof and having transversely flattened portions for moving in the slots of the sleeve to permit the knob to move angularly with respect to the sleeve when the said push pins are in predetermined positions with respect to the sleeve, the flange having an inwardly extending pin and the plate having an arc-shaped slot through which the pin extends, and mechanism adapted to be operated by the movement of the pin of the flange, and means on the said mechanism for engagement by the pin of the hub to return the said mechanism to its original position. 100

105 4. A lock of the character specified, comprising a plate having a central opening, a sleeve having a plurality of series of longitudinally extending alined slots, each slot having a substantially circular enlargement intermediate its ends, said sleeve having a hub received in the opening of the plate, a knob comprising a body received within the sleeve and having an annular radially offset flange fitting outside the sleeve, the said body and flange having alined circular openings adapted to register with the enlargements of the slots, push pins in the openings, a spring normally pressing each of the said push pins outward, each of the said pins having a head for limiting the inward movement thereof and having transversely flattened portions for moving in the slots of the sleeve to permit the knob to move angularly with respect to the sleeve when the said push pins are in predetermined positions with respect to the sleeve, the flange having an inwardly extending pin and the plate having an arc-shaped slot through which the pin extends, and mechanism adapted to be operated by the movement of the pin of the flange, and means on the said mechanism for engagement by the pin of the hub to return the said mechanism to its original position. 110

115 5. A lock of the character specified, comprising a plate having a central opening, a sleeve having a plurality of series of longitudinally extending alined slots, each slot having a substantially circular enlargement intermediate its ends, said sleeve having a hub received in the opening of the plate, a knob comprising a body received within the sleeve and having an annular radially offset flange fitting outside the sleeve, the said body and flange having alined circular openings adapted to register with the enlargements of the slots, push pins in the openings, a spring normally pressing each of the said push pins outward, each of the said pins having a head for limiting the inward movement thereof and having transversely flattened portions for moving in the slots of the sleeve to permit the knob to move angularly with respect to the sleeve when the said push pins are in predetermined positions with respect to the sleeve, the flange having an inwardly extending pin and the plate having an arc-shaped slot through which the pin extends, and mechanism adapted to be operated by the movement of the pin of the flange, and means on the said mechanism for engagement by the pin of the hub to return the said mechanism to its original position. 120

125 6. A lock of the character specified, comprising a plate having a central opening, a sleeve having a plurality of series of longitudinally extending alined slots, each slot having a substantially circular enlargement intermediate its ends, said sleeve having a hub received in the opening of the plate, a knob comprising a body received within the sleeve and having an annular radially offset flange fitting outside the sleeve, the said body and flange having alined circular openings adapted to register with the enlargements of the slots, push pins in the openings, a spring normally pressing each of the said push pins outward, each of the said pins having a head for limiting the inward movement thereof and having transversely flattened portions for moving in the slots of the sleeve to permit the knob to move angularly with respect to the sleeve when the said push pins are in predetermined positions with respect to the sleeve, the flange having an inwardly extending pin and the plate having an arc-shaped slot through which the pin extends, and mechanism adapted to be operated by the movement of the pin of the flange, and means on the said mechanism for engagement by the pin of the hub to return the said mechanism to its original position. 130

said push pins outward, each of the said pins having a head for limiting the inward movement thereof, and having transversely flattened portions for moving in the slots of the sleeve to permit the knob to move angularly with respect to the sleeve when the said push pins are in predetermined positions with respect to the sleeve, the flange having an inwardly extending pin and the plate having an arc-shaped slot through which the pin extends, and mechanism adapted to be operated by the pin.

4. A lock of the character specified, comprising a fixed sleeve having a plurality of series of circumferentially extending alined slots having a substantially circular enlargement intermediate its ends, a knob received within the sleeve, said knob having a radial opening registering with each slot of the sleeve, push pins in the opening, each of the said pins having a transversely flattened portion for engaging and moving in the adjacent slot, and springs for holding the pins in a predetermined position.

5. A lock of the character specified, comprising a fixed sleeve having a plurality of series of circumferentially extending alined slots having a substantially circular enlargement intermediate its ends, a knob received within the sleeve, said knob having a radial opening registering with each slot of the sleeve, push pins in the opening, each of the said pins having a transversely flattened portion for engaging and moving in the adjacent slot, and springs for holding the pins in a predetermined position.

30

said pins having a transversely flattened portion for engaging and moving in the adjacent slot, and means for holding sundry 35 of the pins with the flattened portions out of register with the slots.

6. A lock of the character specified, comprising a fixed sleeve having a plurality of series of circumferentially extending alined 40 slots each having a substantially circular enlargement intermediate its ends, a knob received within the sleeve, said knob having a radial opening registering with each slot of the sleeve, and push pins in the opening, 45 each of the said pins having a transversely flattened portion for engaging and moving in the adjacent slot.

7. A lock of the character specified, comprising a fixed sleeve and a knob rotatable 50 in the sleeve, said knob having radial openings and the sleeve having circumferentially extending slots registering with the openings, each slot having a substantially circular enlargement, a push pin in each opening, each push pin having a flattened portion 55 for engaging and moving in the adjacent slot, and springs for holding sundry of the pins with the flattened portion out of register with the slots.
